AMPULLA SYRINGE

Anni Saek, Basel, Switzerland

Application April 4, 1941, Serial No. 386,933
In Switzerland May 6, 1940

3 Claims. (Cl. 128—272)

1

The present invention relates to an ampulla-syringe having a liquid-container which is transparent and compressible at least in its part forming the container body and comprises an attachment device for a hollow injection-needle. The material for the body of the liquid-container may consist of a transparent, plastified artificial resin, hardened gelatine, an appropriate lacquer mass, a convenient cellulose material or transparent chlorinated caoutchouc or any other similar substance provided that the same is transparent and compressible and in general possesses the properties required for ampullae. An injection needle may be removably connected to the head portion of the container by screw threads or other connecting means. The rigid part of the liquid-container can itself be so formed that the fixation of a usual injection-needle thereon will be possible without difficulties. Furthermore, the head part of the liquid-container can also be constructed as a receptacle with pierceable bottom for the reception of a powdered dry substance or as a receptacle with pierceable bottom for the reception of a liquid solvent for a dry substance within the container body.

The accompanying drawing represents several embodiments of the improved ampulla-syringe.

Fig. 1 shows the preferred form of the present ampulla in longitudinal section.

Fig. 2 shows in longitudinal section a second form of the ampulla embodying the present invention.

Fig. 3 represents a further form of the ampulla in longitudinal section; while

Fig. 4 shows still another form of the ampulla in longitudinal section.

Fig. 5 represents a convenient piercing needle.

In the form of Fig. 1, *a* indicates the body of the liquid-container, which consists of transparent, compressible material of the above kind and is provided with a rigid head part. The head part *b* terminates in a socket *c* which is closed before use of the ampulla by means of a thin closing member *d*. The latter can be pierced or torn-off for the use of the ampulla. In this example it has the form of a cup, but it could also consist of a simple closure film or a closure film with a tearing-off ear or the like. The socket *c* is designed to receive and removably hold a hollow injection-needle, for example by putting, threading or fixing otherwise the same thereon.

The head part *b* of the ampulla is removably connected with the body *a* of the liquid-container by means of a screw thread *e* so that it can be removed therefrom. The said movable connec-

2

tion allows separate cleaning of the head part and facilitates the filling of the ampulla, while the transparency of the body thereof makes possible a constant check upon the purity of its content.

In the modification of Fig. 2, the body *a* of the liquid-container is closed at the upper end by a thin closure plate *f* provided with a peripheral screw thread *g* for receiving the threaded head part *b* of the container and designed to separate the interior of said liquid-container from the interior of the head part *b*. The plate *f* is itself screwthreadedly mounted on the body *a*, as clearly shown in Fig. 2.

In the embodiment of Fig. 3, the body *a* of the liquid-container is closed by a closure piece *h* provided with a funnel-like cavity to form a receptacle or compartment with a thin bottom *h*¹ for receiving a powdered dry substance. In the body *a* itself there is a liquid for dissolving the dry substance, for example water. The cavity of the closure piece *h* is closed at the top by a closing plate *h*². The head part *b* with the socket *c* for receiving the injection-needle is screwed on the closure piece *h*. When the thin closing members *h*¹ and *h*² of the closure piece *h* are pierced, the dry substance runs down through the formed orifice into the liquid solvent in which it dissolves itself. In this example, the closure film *d* of the socket *c* is shown provided with a tearing-off ear *d*¹.

The embodiment of Fig. 4 is similar to that of Fig. 3. The head part *b* constitutes a liquid-vessel or compartment with thin pierceable bottom *i*, whilst the body *a* of the liquid-container encloses a dry substance. When the bottom *i* is pierced, the liquid runs from the head part *b* to the dry substance and dissolves the same to form the solution to be injected.

In the represented construction, with exception of that of Fig. 2, for use of the ampulla-syringe, the closing film of the socket *c* is pierced or removed and then the latter is provided with an injection-needle of known kind. In Fig. 2, the injection-needle *x* is rigidly connected with the socket *c*.

Before using the ampulla-syringe in this case, the closing plate *f* is pierced by means of a piercing needle *y* represented in Fig. 5. In a similar manner will be effected the piercing of the closing membrane parts *h*², *h*¹ in Fig. 3 or *i* in Fig. 4. By compressing the transparent body *a* of the container by hand or by means of a pressure device, the contents of the container can easily be injected.

In all the examples, the transparency of the container body affords a great advantage over the known syringes where the container body consists for example of compressible tin inasmuch as the constant vision of the liquid is possible. Also the fabrication of the improved syringe is simpler and cheaper than in the case of metal ampullae. Finally the injection-needle, which is to be disinfected for use, can be employed several times, whilst in the usual ampullae-syringes it can only once be used.

What I claim is:

1. An ampulla-syringe comprising a liquid-container having a body of transparent, compressible material, a rigid hollow head part thereon and subject to pressure upon compression of said body, means on said head part for supporting an injection needle, and means removably interconnecting said body and head part while securely retaining the same in interconnected rela-

tionship against the influence of the pressure generated upon the compression of said body, said last-named means comprising a closure member arranged between said head part and said body and separating the interiors thereof from each other, said closure member being in screw-threaded engagement with said body and with said head part.

2. An ampulla syringe according to claim 1, wherein said closure member is hollow and comprises a pierceable wall constituting a closure for the interior thereof.

3. An ampulla syringe according to claim 1, wherein said closure member is a thin disk and is provided with a peripheral rib which is externally screw-threaded for screw-threaded engagement with said head and is internally screw-threaded for screw-threaded engagement with said body.

ANNI SACK.
